UNITED STATES PATENT OFFICE.

JAMES M. FLACK, OF SHARON, NORTH CAROLINA.

MECHANISM FOR OPERATING CHURN-DASHERS.

SPECIFICATION forming part of Letters Patent No. 359,145, dated March 8, 1887.

Application filed November 11, 1886. Serial No. 218,594. (No model.)

To all whom it may concern:

Be it known that I, JAMES M. FLACK, a citizen of the United States, residing at Sharon, in the county of Cleveland and State of North Carolina, have invented new and useful Improvements in Mechanism for Operating Churn-Dashers, of which the following is a specification.

This invention has for its object to provide a novel and simple mechanism for imparting a rotary reciprocating to-and-fro motion to the dasher of a churn; and to such end the invention consists in the features of construction and combination of devices hereinafter described and claimed, reference being made to the accompanying drawings, in which—

Figure 1 is a perspective view of my improved mechanism in connection with a churn; Fig. 2, a vertical central sectional view of the same, and Fig. 3 a detail plan view of the cross-head on the operating-lever.

In order to enable those skilled in the art to make and use my invention, I will now describe the same in detail, referring to the drawings, where—

The numeral 1 indicates a supporting-base to which is secured a standard, 2, to the upper end of which is mortised the inner end of a bracket-arm, 3, while to the extreme upper end is mortised a similar bracket-arm, 4, these arms projecting horizontally at right angles to the standard and parallel to each other. The standard between the arms is formed into a journal, 4^a, which is a circle in cross-section, and on this journal of the standard is loosely mounted a horizontal lever, 5, having a handle, 6, and a circular orifice through which the journal passes, thereby permitting the lever to be oscillated in a horizontal plane on the standard between the upper and lower bracket-arms. The inner end of the lever is provided with a cross-head, 7, secured midway of its length to the lever and provided at its top and bottom edges, at opposite ends, with the bevels 45 or inclines 8, whereby one end of the lever is higher than the other end, as clearly shown in Fig. 1, which construction is for a purpose hereinafter explained.

A circular shaft, 9, having a journal, 10, at each end, is located in a vertical plane between

the outer ends of the bracket-arms, the respective journals of said shaft being loosely located in circular orifices in the outer ends of said bracket-arms. To the upper and lower portions of the shaft 9 are respectively secured one 55 end of straps 11, the said straps being partially wound around the shaft in reverse or opposite directions, and the uppermost strap is carried to and connected with the highest end, 12, of the cross-head, while the other strap is carried 60 to and connected with the lowest end, 13, of the cross-head. Thus it will be seen that by the upper and lower beveled edges of the cross-head the straps, in operation, will not interfere with each other, but each will operate on its 65 special part of the shaft 9 when the lever is oscillated. The lower journal of the shaft 9 is extended through the lower bracket-arm, and to it is secured one end of a sleeve, 14, having an angular socket in its other end receiving 70 the squared upper end of the dasher-rod 15, where it can be detachably secured by a pin, 16, or other device.

The dasher-rod carries cross-arms 17, and at its lower end is furnished with a slat having 75 its ends bifurcated, as at 18, the object being to permit the bifurcations to penetrate the butter, so that the latter can be lifted from the churn. The upper end of the dasher-rod being detachably held in the socket of the sleeve 80 14 can be readily removed therefrom and the dasher then lifted from the churn.

As the bracket-arms are mortised on the standard by simply providing said arms with squared orifices fitted to correspondingly-shaped parts on the standard, and as the standard itself forms the journal for the lever between the bracket-arms, the construction is economical and readily constructed of wood, while the sleeve will be of metal. 90

The lower bracket-arm constitutes a rest on which the lever bears in its oscillatory movements; and all the parts being separable they can be detached and stored away in a suitable place until required for use. 95

I am aware that it is not broadly new to operate the dasher-rod of a churn by straps passing from the dasher-rod to arms on a swinging lever pivoted on a standard, as in Letters Patent Nos. 240,508 and 264,598. My construc- 100

tion, as described and claimed, differs therefrom in a lever journaled intermediate its ends on a standard and having at its inner end a cross-head located at right angles to the lever and swinging between the upper and lower brackets at a point between the journaled part of the lever and the outer ends of the brackets in which the shaft is journaled that connects with the dasher-rod. I also so bevel the single cross-head that one end is higher than the other end, so that the straps move without interference with each other. The entire construction is simple, useful, and substantial.

Having thus described my invention, what I claim is—

The combination of the standard, the upper and lower bracket-arms separably mounted on the standard to provide an intervening space, the lever journaled intermediate its ends directly on the standard between the inner ends

of the bracket-arms, and provided at one end with a cross-head located at right angles to the lever and having its upper and lower edges respectively at opposite sides of the lever beveled, as described, and vibrating endwise between the two bracket-arms at a point intermediate the journaled part of the lever and the outer free ends of said arms, the shaft journaled at its upper and lower ends in the free ends of the bracket-arms, and the straps connected with the shaft and the ends of the cross-head, substantially as and for the purposes described.

In testimony whereof I have affixed my signature in presence of two witnesses.

JAMES M. FLACK.
